UNITED STATES PATENT OFFICE.

BERNICE D. WEST, OF NEW YORK, N. Y.

DESIGN FOR AN ORNAMENT FOR AUTOMOBILES.

Application filed January 12, 1929. Serial No. 29,582. Term of patent 7 years.

To all whom it may concern:

Be it known that I, BERNICE D. WEST, a citizen of the United States, residing at New York, county and State of New York, have invented a new, original, and ornamental Design for use as an Ornament for Automobiles, of which the following is a specification, reference being had to the accompanying drawing, forming part thereof.

The figure is a perspective view of an ornament for automobiles, showing my new design.

I claim:

The ornamental design for an ornament for automobiles as shown.

BERNICE D. WEST.
